UNITED STATES PATENT OFFICE.

CHESTER J. SQUIRES, OF GALESBURG, ILLINOIS, ASSIGNOR, BY DIRECT AND MESNE ASSIGNMENTS, OF THREE-FOURTHS TO J. H. WEIDENHAMER, ONE-EIGHTH TO E. C. SHAW, AND ONE-EIGHTH TO C. R. WHITTIMORE, ALL OF GALESBURG, ILLINOIS.

KEYLESS PADLOCK.

Application filed January 16, 1920. Serial No. 351,878.

To all whom it may concern:

Be it known that I, CHESTER J. SQUIRES, a citizen of the United States, residing at Galesburg, in the county of Knox and State 5 of Illinois, have invented new and useful Improvements in Keyless Padlocks, of which the following is a specification.

My invention relates to certain new and useful improvements in keyless padlocks, 10 the object of which is to provide a padlock that can be locked or unlocked by touch, in daylight or darkness, without the necessity of carrying a key for that purpose.

I attain these objects by the mechanism 15 illustrated in the accompanying drawing, in which—Fig. 1 is a front view of my padlock. Fig. 2 is an inner view of one of the interlocking members. Fig. 3 is a side elevation showing the laminated construction. 20 Fig. 4 is a cross section. Fig. 5 is a top view from above downwards.

Similar numerals refer to similar parts throughout the several views.

As illustrated in the drawings, my padlock 25 comprises two substantial circular members 2 interlocked together for relative rotation, each member having an upper curved arm to provide the usual padlock hoop. The members 2 may be formed of any suitable material, but I preferably form 30 each of stamped lamination 2¹, 2² and 2³ and provide interiorly of each member a plurality of interlocking tongues or flanges 3 shown in plan view in Figure 2 and in 35 interlocked relation in Figure 4. Near the outer circumference of each member, there are provided a plurality of similar apertures 4; each aperture comprising an inner enlarged bore and an outer restricted bore. 40 These apertures receive the combination pins 1 which are provided with enlarged heads at their inner ends against which springs 5 housed in the enlarged bores bear.

It should be noted that the majority of 45 pins such as 1³ have the same sized head and are of equal length and are yieldingly held in abutting relation by equal tension springs 5 when the apertures are in register, so that their abutting plane coincides with the dividing plane of the members 2. One 50 or more pins such as 1¹ are however so constructed or so stressed by their springs that their abutting planes with the adjacent pins 1² when the apertures are in register is to

the opposite side of the dividing plane; the 55 pins 1¹ thus projecting beyond the dividing plane will lock the members 2 together with the arms in close contact forming the shackle of the padlock as is obvious. To accomplish this result, the locking pins 1¹ are 60 preferably longer and more highly stressed than their adjacent pins 1² which are more weakly stressed and are shorter so (see Fig. 4) that when they are forced outwardly by the unequal tension, their ends will not project beyond the other pins, and the symmetry will not be destroyed to afford detection whereby said pins are arranged in undistinguishable array. The locking pins 1¹ are also preferably provided with longer 65 heads which are sufficient to extend across the dividing plane of the members 2 in their locking relation.

It is obvious that any number of locking pins 1¹ may be provided and placed anywhere, and may be changed as often as desired to different apertures to change the combination, thus they might be placed in any aperture from 1 to 8; they may also be placed in either member, and the shorter 80 coacting pins 1² placed in the opposite member.

The shorter pins 1² adjacent the locking pins constitute the unlocking pins or members, and when it is desired to unlock the 85 two members for relative rotation, the shorter pins are pressed or pushed against the longer locking pins 1¹ until their abutting plane coincides with the dividing plane of the members 2.

The arms that form the shackle of the padlock are preferably milled to provide a tongue and groove joint 6 in order to prevent lateral shifting of the arms.

I have entered into a detailed description 95 of the construction and relative arrangement of the parts comprised in the present and preferred embodiment of my invention in order to impart a full, clear exact understanding of the said embodiment. I do not 100 desire, however, to be understood as confining myself to the said specific construction and relative arrangement of parts as in the future practice of the invention such changes or modifications may be made, as 105 fairly fall within the scope of my appended claims.

Having described my invention, what I

claim and desire to secure by Letters Patent is:—

1. In a padlock, a pair of relatively rotational members each having a series of similar apertures adapted to be brought into registry when said members are in locking position, equally spring stressed similar pins in some of said apertures, and unequally spring stressed pins of different lengths in other apertures, the larger of the latter mentioned pins forming the locking element.
2. In a padlock, a pair of relatively rotational members held in interlocking relation, each member having a series of similar apertures adapted to be brought into registry when said members are in locking position, a locking pin and an unlocking pin arranged in registering apertures, and other pins arranged in the other apertures, and means for properly yieldingly stressing said pins.
3. In a padlock, a pair of relatively rotational members having interlocking tongues for holding the same for relative rotational movement, a series of slideable spring pressed pins carried by each member and adapted to be brought into alinement by rotational movement of said members, said pins projecting beyond the outer surfaces of said members in undistinguishable array when said members are locked together, and one pair of said alined pins being of unequal length and the longer of the two having

greater spring pressure exerted thereagainst whereby it will shift beyond the abutting plane of said members for locking the same together.

4. In a padlock, a pair of relatively rotational members, each having a circular series of apertures adapted to be brought into alinement when said members are rotated to locking position, pins of equal length yieldingly retained in certain of said alined apertures, pins of unequal length having a combined length equal to the combined length of the other pins yieldingly retained in other alined apertures by unequal spring pressure, the longer thereof being more strongly stressed whereby they will shift beyond the abutting plane of said members for locking the same together.

5. In a padlock, a pair of relatively rotational members, each having a pair of raised tongues on the inner surface thereof, with the tongues of one member positioned under the tongues of the other member for interlocking said members for relative rotational movement.

In testimony whereof I affix my signature in the presence of two witnesses,

CHESTER J. SQUIRES.
